UNITED STATES PATENT OFFICE.

GEORGE J. HARTKE, OF CINCINNATI, OHIO.

ENVELOP.

1,031,550.

Specification of Letters Patent.

Patented July 2, 1912.

Continuation of application Serial No. 403,711, filed November 25, 1907. This application filed December 21, 1908. Serial No. 468,569.

To all whom it may concern:

Be it known that I, GEORGE J. HARTKE, a citizen of the United States, residing at Cincinnati, in the county of Hamilton and 5 State of Ohio, have invented certain new and useful Improvements in Envelops, of which the following is a specification.

The present invention relates to an envelop of the class shown and described in 10 Letters Patent No. 532,206 granted January 8th, 1895, to A. D. Klaber which is known to the trade by the name "Neostyle."

The Neostyle envelop as shown in the patent and as heretofore made is open to 15 several objections. One of these is that during the filling operation the loose side flap is held in place only by reason of the fact that it projects a short distance beneath, or, to state it differently, is partly overlapped by 20 the adjacent side of the bottom flap but otherwise it is not engaged by any part of the envelop that would have a tendency to hold it in place. Being loose and disengaged, except as aforesaid, when the envelop 25 is being filled, it is sometimes forced upward and outward and freed from engagement with the bottom flap. This is apt to happen frequently unless the operator is experienced. Another objection to 30 the Neostyle envelop as heretofore made is that even after it is filled and sealed, the loose flap is sometimes freed from its engagement with the top and bottom flaps and forced out. This may happen when 35 pressure is suddenly exerted upon the sealed envelop, especially when several of them are piled up, one upon another, immediately after being sealed. When first sealed a considerable volume of air is imprisoned in 40 the envelop and the sudden expulsion of this air incident to compressing the pile of envelops, blows the loose flap out. Again the loose flap is sometimes forced out as the mail is being distributed or otherwise 45 handled. This will happen if the envelop with its inclosure is so handled that the inclosure is thrown against the loose flap, especially if the inclosure is heavy.

The object of the present invention is to 50 provide an envelop which has all the advantages of the Neostyle and which, at the same time shall be free from the objections above pointed out.

To this end the invention consists in the

features of novelty that are hereinafter described.

In the accompanying drawing which is made a part of this specification, Figure 1 is a diagrammatic representation of an envelop partly folded, embodying the invention. 60 For the purposes of this application this is elected as the preferred form of the invention. Figs. 2 and 3 are similar views showing modifications.

In all of the figures of the drawing similar parts are indicated by similar reference letters.

A represents the front of the envelop, B the top or sealing flap, C the bottom flap, D the loose side flap and E the remaining 70 side flap, the flaps C and E being fixedly secured together as hereinafter described. The drawing shows the side flaps folded to the positions which they occupy in the completed envelop, and shows the top and bottom flaps as they appear in the blank, the positions which they occupy in the completed envelop, after the blank is folded on the dotted lines *a* and *a'*, being indicated by the dotted lines *b* and *c*, respectively. 80

In folding the envelop, the side flap E, is first folded down upon the front A. The loose side flap D is then folded down upon the front, and also upon the side flap E to the extent of a portion *d* which overlaps it. The bottom flap C is then folded down upon the front A and also upon both of the side flaps. The adjacent sides of the bottom flap and the loose side flap overlap each 85 other but they are not united in any way. The bottom flap C is then folded down upon the front A and also upon both of the side flaps. A portion of the bottom flap overlaps and lies upon the outside of a portion of the loose side flap but they are not united 90 in any way. A portion of the bottom flap C also overlaps and lies upon the outside of a portion of the side flap E, and limited areas of the surfaces of their overlapping portions are fixedly united or secured together by any suitable adhesive substance 95 as shown by the shade lines F, thus leaving other limited areas of the surfaces of the overlapping portions ununited forming a pocket as shown at *f*. This adhesive substance may be applied to either or both of the 100 said flaps, C and E, indifferently. The shade lines on the several flaps are not in-

tended to show to which of the flaps the adhesive substance is initially applied, but, rather, to show the relative areas of the united and the ununited surfaces of the 5 overlapping portions of the several flaps when the envelop is complete and sealed or ready to be sealed. In the forms of the invention shown in Figs. 1 and 2 the ununited surfaces of the overlapping portions of the 10 fixedly united flaps C and E occur at an intermediate point in the general line of the adhesive substance uniting said flaps, or in other words, at a point which breaks or interrupts said line, so that upon opposite 15 sides of the ununited surfaces of the overlapping portions, said overlapping portions are united; while in the form of the invention shown in Fig. 3 the ununited surfaces of the overlapping portions occur at one 20 extremity of the line of adhesive substance, the united surfaces of the overlapping portions thus occurring at one side only of the ununited surfaces. In either event the un- 25 united portions of the two flaps form a pocket for receiving a portion *d* of the loose flap, D, while the united portions form what may appropriately be called a stop, *f'*, which, of course, is carried by the envelop and is immediately adjacent to the pocket 30 above it or below it as the case may be, but preferably above it. In all of the several forms of the invention shown in the drawing the portion *d* of the loose flap lies between the ununited surfaces of the overlapping 35 portions of the flaps C and E. This in itself (without the features presently mentioned) will aid materially in preventing the accidental displacement of the loose flap but in order to more effectually prevent its 40 displacement the portion *d* is so shaped as to form a shoulder *d'* the working side of which is presented angularly, more or less abruptly, toward the stop and toward the side of the envelop which carries the loose 45 flap. The shoulder is also preferably presented upward as shown in Figs. 1 and 2, rather than downward as shown in Fig. 1, because in filling the envelop the pressure against the loose flap tends to move it upward, but it is effectually prevented from moving upward by engaging the under side of the stop. But whether presented upward or downward the shoulder will engage the rear side of the stop and the loose flap effectually prevented from being accidentally blown or forced out by pressure within the envelop acting directly outward upon it, while at the same time it will not be prevented from being purposely drawn out by proper 50 manipulation, for allowing the contents of the envelop to be inspected. In doing this the natural tendency is to draw the loose flap outward and downward and its downward movement frees the shoulder from the 55 stop without tearing it. Preferably, also, 60

the end of the portion *d* of the loose flap takes the form of a hook which extends beyond and behind, as it were, the stop, *f'*, the working side or shoulder *d'* of the hook being presented quite abruptly toward the 70 side of the envelop which carries the loose flap, as shown in Fig. 1.

In all of the several forms of the invention shown in the drawing the top or sealing flap B, is gummed, as shown at *b'*, along those portions of its surface which contact with the bottom flap C and the side flap E when the envelop is sealed, the gum being omitted from those portions of the sealing flap B that overlap and contact with the 75 loose flap D or any part thereof. For example, in each of the several forms of the invention shown in the drawing the gum is omitted from the sealing flap at *b''*, where it overlaps and contacts with the main portion of the loose flap D, and in like manner it will be omitted at any point that might possibly contact with the projecting portion *d* of the loose flap. The sealing flap, is however, preferably of sufficient width to 80 completely cover and extend below the portion *d* so as to bring the line *b'* of gum completely below said portion *d* and also completely below the pocket, as shown more 85 clearly in Fig. 3. In other words, whatever 90 desired proportion of the extent to which the sealing flap overlaps the fixed end flap E and bottom flap C, may be gummed.

The subject matter of this application was 95 shown and described in a former application filed Nov. 25, 1907, serial No. 403,711.

What I claim as new and desire to secure by Letters Patent is:

1. An envelop having a front, a bottom flap and a side flap, said bottom and side flaps having overlapping portions, means for fixedly uniting limited surface areas of said overlapping portions, thereby forming a stop, and leaving limited surface areas of said overlapping portions ununited, thereby forming a pocket adjacent to the stop, and a loose side flap, opposite the fixed side flap aforesaid, said loose side flap being overlapped by the fixed bottom flap and having a portion occupying said pocket and lying between the ununited portions of said overlapping portions of the fixed bottom and side flaps.

2. An envelop having a front, a bottom flap and a side flap having overlapping portions, means for fixedly uniting limited surface areas of said overlapping portions, thereby forming a stop, and leaving limited surface areas of said overlapping portions below said stop ununited, thereby forming a pocket, and a loose side flap opposite the fixed side flap aforesaid, said loose side flap being overlapped by the fixed bottom flap and having a portion lying between the un- 120 united portions of the overlapping portions 125 130

of the fixed bottom and side flaps and adapted to engage the bottom side of the stop.

3. An envelop having a front, a bottom flap and a side flap, said side flap being overlapped by the bottom flap, means for fixedly uniting limited surface areas of the overlapping portions of said flaps, thereby forming a stop, and leaving limited surface areas of said overlapping portions ununited, thereby forming a pocket adjacent to said stop, and a loose side flap opposite the fixed side flap aforesaid, said loose flap being overlapped by the fixed bottom flap and having a portion lying between the ununited portions of said overlapping portions of the fixed bottom and side flaps, that portion of the loose flap which lies between said ununited portions of the fixed bottom and side flaps having an angularly disposed shoulder presented toward the rear side of the stop.

4. An envelop having a front, a bottom flap and a side flap, the side flap being overlapped by the bottom flap, means for fixedly uniting limited surface areas of said overlapping portions, thereby forming a stop, and leaving limited surface areas of said overlapping portions below said stop ununited, thereby forming a pocket below the stop, and a loose side flap opposite the fixed side flap aforesaid, said loose side flap being overlapped by the fixed bottom flap and having a portion lying between the ununited portions of the overlapping portions of the fixed bottom and side flaps and adapted to engage the bottom of the stop, that portion of the loose flap which lies between the ununited portions of the overlapping portions of the fixed bottom and side flaps having on its top side an angularly disposed shoulder presented toward the rear side of the stop.

5. An envelop having a front, a side flap, a bottom flap overlapping the side flap, means for fixedly uniting limited surface areas of said overlapping portions, thereby forming

a stop, and leaving limited surface areas of said overlapping portions ununited, a loose side flap overlapped by the fixed bottom flap and having a portion lying between the ununited portions of said overlapping portions of the fixed bottom and side flaps, a fourth or sealing flap overlapping the fixed bottom and side flaps and also the loose flap, and an adhesive substance for uniting the sealing flap to at least one of the fixed flaps.

6. An envelop having a plurality of flaps and a stop, one of said flaps being loose and provided with a portion lying between ununited overlapping portions of two of the other flaps, and another of said flaps being a closing or a sealing flap which overlaps all of the other flaps, on the outside thereof, and an adhesive substance for uniting said sealing flap with at least one of the fixed flaps, leaving the loose flap free to be withdrawn.

7. An envelop comprising a plurality of flaps, sealing means for securing one of said flaps to another along one edge, an interruption in said sealing means, and a flap having an angularly disposed tongue adapted to project through the sealed edge at said interruption.

8. An envelop comprising a plurality of flaps, means for securing said flaps along one side, said flaps being unsecured along the other side, an interruption in said securing means, and a loose flap having an angular end adapted to project through the securing means of said interrupted portion.

9. An envelop comprising a plurality of flaps, means for securing said flaps together at their edges, an interruption in said securing means, a loose flap having its edges covered by the secured flaps when in closed position, said loose flap having an end passing between and projecting beyond said flaps at said interruption.
